UNITED STATES PATENT OFFICE

2,441,424

SHADE AND CURTAIN HANGER

John Kroll, Detroit, Mich.

Application October 26, 1946, Serial No. 705,859

6 Claims. (Cl. 248—252)

1

This invention relates to improvements in shade and curtain hangers.

An object of the invention is to provide an improved shade and curtain hanger which will be adapted to be clamped to and supported by the opposite vertical side strips or panels of a window frame.

Another object of the invention is to provide an improved shade and curtain hanger which will be adjustable to fit various widths of windows having various width of side frame facing members.

A further object of the invention is to provide an improved adjustable shade and curtain hanger construction which will be clamped on the opposite outer side frame members on a double window and on the central frame member between said windows to adjustably support the shades for said windows and a curtain supporting pole in position above said windows.

Another object of the invention is to provide an improved shade and curtain hanger which will be highly efficient in operation and relatively inexpensive to manufacture and produce.

Other objects will appear as the description proceeds.

In the accompanying drawings which form a part of this application,

Figure 1 is a perspective view of an improved shade and curtain hanger shown in position upon a side window frame which is illustrated in broken lines;

Figure 2 is a view taken on the line 2—2 of Figure 1;

Figure 3 is a view partly in section taken on the line 3—3 of Figure 1;

Figure 4 is a perspective view of a double shade and curtain bracket adapted for clamping to the middle of a double window frame;

Figure 5 is a perspective view of a side drape support positioned upon the improved curtain hanger, and

Figure 6 is a partial sectional view taken on the line 6—6 of Figure 5.

Like characters of reference are used throughout the following specification and the accompanying drawings to designate corresponding parts.

In carrying out the invention, there is provided an improved shade and curtain hanger having oppositely disposed clamping arms 1 and 2 adapted for clamping upon the opposite side surfaces of the side frame members 3 of a window frame generally denoted by the reference numeral 4, to extend forwardly thereof to support

2

a roller shade 5 and a transversely extending curtain pole 6.

A pair of spaced tie rods 7 and 8 are connected between the clamping arms 1 and 2 in spaced relation, and are threaded as at 9 on one end to support the nuts 10 for tightening the shade and curtain hanger upon the window frame.

The wood bracing and positioning rod 11 is disposed about the tie rod 8, and is formed with the oppositely disposed slots 12 and 13, and the oppositely disposed slots 14 and 15 in spaced relation thereto for purposes hereinafter described.

The improved shade hanger comprises a thin body or plate 16 having a forwardly extending head 17 at its upper end formed with the spaced parallel forwardly extending positioning fingers 18 and 19, which are adapted to be received in the spaced slots 14 and 15 in said rod 11. The rear end of said body or plate 16 is apertured to receive the transversely extending tie rod 7 to hold the same in fixed adjusted position. A forwardly extending head 20 is formed on the lower end of the body or plate 16 and is formed with either an aperture 21 or slot 22 for supporting the particular elements at the desired end of the roller shade 5, said shade bracket depending below the level of said clamping arms 1 and 2.

The improved curtain rod support or bracket is formed quite similarly to the shade bracket, but extends upwardly above the clamping arms 1 and 2, and comprises a body or plate 23 formed with a forwardly extending actuate pole supporting arm 24 adjacent its upper end, and with the forwardly extending head 25 at its lower end formed with the spaced parallel forwardly extending fingers 26 and 27 adapted to be received in the spaced slots 12 and 13 formed in the rod 11. Similarly, the rear end of the head member 25 is apertured to receive the transversely extending tie rod 7, to brace and hold said curtain rod support in the desired adjusted position.

In Figure 4 of the drawings, there is illustrated a double shade and curtain bracket formed identically with the single bracket with the exception that the tie rods and wood bracing rod are longer, and are formed with four sets of spaced parallel slots for receiving and positioning two shade brackets and two curtain pole supporting brackets. It will be understood that this form of shade and curtain bracket will be clamped to the middle double width frame member in the center of a double window frame.

In Figure 5 of the drawings, there is illustrated an attachment for positioning upon a

curtain rod bracket, the same comprising a forwardly extending body or plate 28 formed with an actuate seat 29 in its upper surface corresponding to the curvature of the actuate seat in the pole supporting arm 24, and secured to said curtain rod supporting body 23 and said arm 24 by means of the rivets 30. A vertically disposed semi-cylindrical bearing plate 31 is secured to the forward end of the plate 28, and pivotally supports the depending pivotal arm 22 on the T-shaped side drape supporting arm 33, which is pointed at 34 on its outer end to facilitate side drapes (not shown) being threaded over said arm 30.

If desired, the shade and curtain hangers may be clamped to the opposite ends of the horizontal top frame member of a window, in which case, the bracket arms 16 and 23 will be bent at right angles to correctly support the curtain pole 6 and roller shade 5.

From the foregoing description, it will be apparent that there has been devised and provided a highly efficient form of shade and curtain rod supporting bracket which will be highly efficient in operation, and relatively inexpensive to manufacture and produce.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention, what I claim as new and desire to secure by Letters Patent of the United States is:

1. A combined shade and curtain hanger comprising a pair of similarly formed horizontally extending parallel clamping arms, spaced tie rods adjustably connected between the same; a shade hanger and a curtain pole hanger slidably mounted on one of said tie rods, and cooperating notched means on said other tie rod and said shade and curtain pole hangers for locking and supporting the same in the desired adjusted position.

2. A combined shade and curtain hanger comprising a pair of similarly formed horizontally extending parallel clamping arms, spaced tie

rods adjustably connected between the same, a shade hanger and a curtain pole hanger slidably mounted on one of said tie rods to extend respectively below and above the same, and notched means on said other tie rod for positively engaging said hangers to support the same in the desired adjusted position.

3. A combined shade and curtain hanger comprising a pair of parallel clamping arms, spaced tie rods adjustably connected between the same, a shade hanger and a curtain pole hanger slidably mounted on one of said tie rods to extend respectively below and above the same, spaced parallel forwardly extending arms formed on said hangers, a wood rod disposed about said other tie rod having spaced parallel extending slots formed therein adapted to receive and lock said spaced parallel forwardly extending arms on said hangers to hold the same in the desired adjusted position.

4. The subject matter as claimed in claim 3, and forwardly extending curtain pole and shade roller supporting arms at the opposite ends of said hangers.

5. The subject matter as claimed in claim 3, forwardly extending curtain pole and shade roller supporting arms at the opposite ends of said hangers, and side drape supporting brackets supported on said curtain rod supporting brackets.

6. The subject matter as claimed in claim 3, forwardly extending curtain pole and shade roller supporting arms at the opposite ends of said hangers, side drape supporting brackets supported on said curtain rod supporting brackets, pivoted side drape supporting arms pivotally supported in said drape supporting brackets, and the outer ends of said arms being sharpened to facilitate the positioning of side drapes thereon.

JOHN KROLL.
